UNITED STATES PATENT OFFICE.

ALVIN KINGSBACHER AND WALTER W. MACFARREN, OF PITTSBURGH, PENNSYLVANIA.

SHUTTLE-BOX FOR LOOMS.

1,275,701.

Specification of Letters Patent. Patented Aug. 13, 1918.

Application filed April 3, 1913. Serial No. 758,650.

To all whom it may concern:

Be it known that we, ALVIN KINGSBACHER and WALTER W. MACFARREN, citizens of the United States, residing at Pittsburgh, in the county of Allegheny and State of Pennsylvania, have invented certain new and useful Improvements in Shuttle-Boxes for Looms, of which the following is a specification.

Our invention relates to looms and more specifically to means for weaving two fabrics at once each having varicolored threads in the filling, whereby any desired patterns can be woven and the production of the loom is greatly increased.

The object of our invention is to provide means for passing two shuttles through two separate sheds at the same time, and to provide means for changing the shuttles at will for others containing different colors according to the requirements of the pattern.

To these ends our invention consists in a rotary shuttle box which may be applied to either or both sides of the loom, means for rotating the shuttle box between picks to present the desired shuttles simultaneously, and a selective latch mechanism for the shuttle box controlled by the pattern chain, together with the various details of construction shown in the drawings, in which:

Figure 1 is a sectional elevation through the shuttle box showing the picker, etc.

Fig. 2 is a plan view of the same.

Fig. 3 is a sectional elevation on the line 35 1—1 of Fig. 2.

Fig. 4 is an elevation of the shuttle box.

Fig. 5 is a cross section of one of the pockets for the shuttles.

Fig. 6 is a diagrammatic plan view of 40 the pattern chain for the filling.

Fig. 7 is a diagrammatic elevation showing the shuttle box in relation to the double shed in the warp.

The general construction of looms and 45 their method of operation being a matter of common knowledge, we have shown only those parts necessary to an understanding of our invention, and as our improved mechanism may be applied to a variety of looms, 50 and may assume a variety of forms, we have represented the same merely diagrammatically.

Referring to the drawings the shuttle box

1 is mounted to rotate freely on the pin 2, supported by the lay sword 3, which latter 55 is secured to the lay shaft 60.

The shuttle box 1 is provided with two series of concentric pockets 4 and 5 to hold the shuttles. Each pocket is provided with a pair of springs 6 to check and hold the 60 shuttle (see Fig. 5).

A slot 7 is formed in the partition 8, between boxes 4, and 5, and a similar slot 9 is formed in the outer wall of the box 5.

A picker 11 is mounted to slide on a 65 square guide bar 12 secured to the lay sword 3, and is provided with a long hub 13, which assures rigidity.

The picker stick 14 is pivoted on a pin 16 fastened to the lay shaft 60 and actuated 70 by the usual rod 17, and spring 18, and is connected to the picker 11 by the link 19. The picker 11 passes through the slots 7 and 9 to actuate the shuttles 10.

A friction band 20 is secured to the shuttle 75 box 1, the same extending around the outer circumference thereof and covering one end of the slots 9. The band 20 is engaged at suitable times by either of a pair of friction wheels 21 and 22, the same being mounted 80 in pivoted frames 23 and 24, and driven by oppositely moving belts 25 and 26, or in any other suitable manner. The wheel 22 is brought into contact with the band 20 by the pattern chain 31. The frame 24 is pivoted 85 on the pin 27 and swung by a vertical rod 28, which works in a guide 29, and is provided with a shoe 30, which latter may be engaged by suitable risers on the pattern chain 31. Similar means operate the frame 90 23 to engage the wheel 21.

The pattern chain 31 is composed of the side links 32 and pins 33 (shown in dotted lines in Fig. 6) and is divided into 8 spaces crosswise. These spaces may contain risers 95 34 or sinkers 35 as usual. The first six spaces A to F are to operate the latch mechanism to be hereinafter described, and the other two spaces G and H are to operate the wheels 21 and 22.

The chain 31 may travel over a rigid guide 36, and when a riser in space H strikes the shoe 30 the wheel 22 is forced into frictional contact with the band 20. This contact lasts only while the riser passes under 105 the shoe 30, and the length of the shoe may

be made to suit the desired interval of contact.

A weight 37 on rod 28 returns the parts to an inoperative position, and similar means actuated by risers in space G of chain 31 actuate the wheel 21.

If desired the shuttle box 1 could be rotated by a single wheel 21 or 22, the other being omitted, but in this case the operation would be slower, as the box 1 would have to be turned at times two-thirds and five-sixths of a revolution, whereas in the arrangement shown it need never be turned more than one-half a revolution.

15 The above means for rotating the shuttle box will operate smoothly and without shock at any speeds at which it is practicable to operate the loom, but as the frictional driving effect is not positive, other means of controlling the exact degree of movement are required, and this is accomplished by a selective latch mechanism as follows:

20 The shuttle box 1 is extended toward the outside of the loom to form a drum 40, and the width of the drum 40, is divided into 6 equal spaces (or as many as there are pockets 4 or 5). Each division of width on the drum 40 is provided with a single notch 41, these notches being set around the circumference at the same angular spacing as the pockets 4 and 5, and each notch controlling a pair of pockets.

25 When the shuttle box 1 is rotated by the wheels 21 or 22, it is only necessary to allow a latch to enter the notch 41 corresponding to the pair of pockets 4 and 5 from which the shuttles are to be drawn, in order to register the shuttles with the warp.

30 40 A stationary shaft 44 carries six loosely mounted latches each connected by a link 46 to a bell crank 47. A set of six vertical rods 48 is mounted in guides 49 and 50, and each rod 48 is provided with a hook 51 at its upper end, each of said hooks controlling a latch 45.

45 Each rod 48 carries a strong spring 52 which normally causes the parts to assume the position shown in Fig. 3 with the collar 53 resting on the guide 50. Each rod 48 carries a shoe 54 which may be engaged by a riser in spaces A to F of chain 31.

50 Such a riser will lift the corresponding rod 48 against the resistance of the strong spring 52 and allow the weaker spring 55 to draw the latch 45 against the circumference of the drum 40.

55 60 As soon as the corresponding notch 41 comes opposite the latch 45 the end thereof will enter the notch and lock the shuttle box 1 in such position that two of the shuttles 10 will be in proper alignment with the lay.

65 As soon as the riser has passed the shoe 54 the spring 52 will withdraw the latch 45

from the notch 41 and at the same instant or slightly before, the wheel 21 (or 22) will be brought to bear on the band 20 to rotate the box again.

70 It will be seen that the risers and sinkers in the various spaces (width) of the chain 31 perfectly control the operation of the shuttle box 1. When it is desired to repeat a pick several times from the same shuttle several risers are placed in the proper latch space (A to F) in consecutive order, and the shoe 54 is made long enough to span the space between adjacent risers so that the latch 45 may remain stationary during the desired number of picks.

75 80 When this is done consecutive sinkers are placed in the spaces G and H and the wheels 21 and 22 are inoperative as regards the shuttle box 1.

85 The above description does not take account of the movement of the lay. The shuttles are changed in the forward position of the lay, and the latches 45 engage the drum 40 in this position. When the lay starts back the shuttle box 1 and drum 90 40 are moved away from the latches thus disengaging the particular latch engaged.

95 In order to hold the shuttle box from turning during the movement of the lay, we provide a friction brake operated by the movement of the lay as follows:

100 A brake block 61 is mounted on a lever 62 the latter being pivotally mounted on a pin 63 and connected to a strong spring 64. A stop 65 limits the motion of the lever 62 so that in the extreme forward position of the lay the brake block 61 is out of contact with the drum 40 and the shuttle box 1 is free to rotate. As soon however as the lay 105 starts back the drum 40 engages the block 61 and carries it along in contact; against the resistance of the spring 64 thus locking the shuttle box 1 against rotation and preserving the setting given it by the latches.

110 Fig. 7 shows the relations of the lay, the shuttle boxes, the reed and the sheds in the rear position of the lay. From spool 67 the threads 68 and 69 are led over the whip roll 70 to form the upper shed 71. The thread 68 passes through the upper eye of the heddle 72 and the thread 69 passes through the upper eye of the heddle 73. These threads form the warp of the upper fabric 74. From spool 75 the threads 76 and 77 are led over the whip roll 70 to form 115 the lower shed 78. The thread 76 passes through the lower eye of the heddle 72 and the thread 77 passes through the lower eye of the heddle 73 these two threads forming the warp of the lower fabric 79. Temples 120 are indicated at 80 and 81.

125 When the heddle 72 is depressed the thread 68 assumes the position shown for thread 69, and the thread 76 that shown for 77. At the same time the heddle 73 is raised 130

and the thread 69 assumes the position shown for thread 68 and thread 77 rises to position shown for thread 76.

Thus the threads 68 and 69 cross each other and the threads 76 and 77 cross each other but neither pair interfere with the other thus weaving two independent fabrics. The reed is indicated at 68.

While the prime object of our invention is to provide means whereby the shuttles may be changed between picks and in any desired order so that two fabrics may be woven at once, each having a variety of colors in the filling it will be obvious that by omitting or not operating certain parts of the mechanism, our improved shuttle box may be used on a loom weaving cloth with but a single color in the filling and our improved shuttle box may be used in this case merely as a means of quickly replacing empty shuttles with full ones.

When so used the full shuttles could be introduced say at the top of the shuttle box.

The operation of our improved mechanism will be readily apparent from the above description to those skilled in the art.

We claim as our invention:—

1. In a loom, means for forming two sheds in the warp, means for passing a shuttle through each of the said sheds at the same time, a movable magazine comprising a plurality of shuttle boxes, one of which supports each of the said shuttles, a pattern controlling mechanism for said magazine, and automatic means controlled thereby to move the magazine for substituting for said shuttles other shuttles containing dissimilar threads to suit the pattern being woven.

2. In a loom, means for forming two sheds in the warp, a rotary shuttle box carrying several pairs of shuttles, a picker arranged to send a pair of shuttles together across the warp, a friction roller in contact with the shuttle box to rotate the same and a latch to register a pair of shuttles with the picker.

3. In a loom, means for forming two sheds in the warp, a rotary shuttle box containing a number of shuttles arranged in pairs, a picker arranged to engage a pair of shuttles and send them together across the warp, a pair of oppositely rotating friction wheels, means for pressing either of said wheels against a part connected to the shuttle box to rotate the same, and a latch for registering a pair of shuttles with the picker.

4. In a loom, means for forming two sheds in the warp, a rotary shuttle box containing a number of shuttles arranged in pairs, a picker arranged to engage a pair of shuttles and send them together across the warp, a pattern chain controlling the filling, means for rotating the shuttle box in either of two

directions controlled by said chain, and a selective latch mechanism also controlled by said chain and arranged to register any desired pair of shuttles with the picker.

5. In a loom, means for forming two sheds in the warp, a rotary shuttle box supported by and moving with the lay, said shuttle box carrying a number of shuttles arranged in pairs, a picker for engaging a pair of shuttles and sending them together across the warp, means for rotating the shuttle box when the lay is forward, means for registering a pair of shuttles with the lay, and a brake for preserving the setting of the shuttle box during the rearward movement of the lay.

6. In a loom, means for forming two sheds in the warp, a rotary shuttle box containing a number of shuttles arranged in pairs, a slot in the outer wall of the shuttle box for each pair of shuttles a second slot in the partition between each pair of shuttles, and a picker acting through said slots to send a pair of shuttles together across the warp.

7. In a loom, means for forming two sheds in the warp, a rotary shuttle box containing a number of shuttles arranged in pairs, a picker, a drum having its width divided into as many spaces as there are pairs of shuttles, a notch for each space, said notches being set around the circumference of the drum in the same angular relation as the shuttle pockets, a series of latches, a pattern chain and means for setting the latches to engage the notches whereby a certain pair of shuttles is registered with the picker.

8. In a loom, means for weaving two pieces of fabric at once, comprising several shuttles arranged in sets of two for simultaneous picking, each set of said shuttles containing threads of one kind or color, and dissimilar from the threads in the other sets of shuttles, a rotatable shuttle box for supporting the shuttles, automatic means for rotating the shuttle box for substituting one set of shuttles for another set to suit the fabric being woven, and a picker arranged to operate a set of shuttles across the lay, in combination with means for forming two sheds in the warp, whereby two separate fabrics may be simultaneously woven each having a pattern containing dissimilar threads in the filling.

In testimony whereof we hereunto affix our signatures in the presence of two witnesses.

ALVIN KINGSBACHER.
WALTER W. MACFARREN.
